(57) **CLAIM**

The ornamental design for a ring packaging insert, as shown and described.

DESCRIPTION

FIG. 1 is a front perspective view of the ring packaging insert, showing our new design;

FIG. 2 is a right side view of the design illustrated in FIG. 1;

FIG. 3 is a left side view of the design illustrated in FIG. 1;

FIG. 4 is a front view of the design illustrated in FIG. 1;

FIG. 5 is a rear view of the design illustrated in FIG. 1;

FIG. 6 is a top view of the design illustrated in FIG. 1;

FIG. 7 is a bottom view of the design illustrated in FIG. 1; and,

FIG. 8 is a perspective view of the ring packaging insert in an open position showing an exemplary charger and ring location within the packaging insert.

The broken lines in the drawings are for the purpose of illustrating unclaimed portions of the ring packaging insert and form no part of the claimed design. Further, surfaces of FIG. 8 that are bounded on one or more sides by a broken line form no part of the claimed design.
